MULTISHUTTLE BOX

Richard Greenleaf Turner, Worcester, Mass., assignor to Crompton & Knowles Loom Works, Worcester, Mass., a corporation of Massachusetts

Application October 1, 1936, Serial No. 103,543

7 Claims. (Cl. 139—184)

This invention relates to improvements for shuttle boxes for looms and it is the general object of the invention to provide a box built up of individual units each of which is complete in itself.

It has been common practice heretofore in the manufacture of fancy looms to cast all the cells of the gang of shifting shuttle boxes in one piece. As a result of this construction it has been difficult to polish the floors and backs of the shuttle boxes without the expenditure of considerable effort. It is an important object of my present invention to provide a built up gang of boxes each cell of which is made of separate pressed steel parts and to bolt the several parts together to form the gang.

Single shuttle boxes have heretofore been lined with a wear resisting smooth material, such as sheet Bakelite or the like, but it has been very difficult to use this material in prior multi-cell boxes because of the problem of securing the sheet material to the cells. It is another object of my invention to provide sheets or plates of a smooth wear resisting material such as Bakelite to be incorporated into the construction of the assembled boxes and held in place by the tie bolts or the like which hold the several cells together.

It is a further object of my present invention to form the guide tongues for the gang on blocks which space the tops and bottoms of the cells and these blocks are preferably made of an improved wearing material, such as Bakelite. The tops and bottoms of the cells are formed with small tongue projections which engage and reinforce the tongues on the blocks.

Where guide tongues of a length greater than the height of the cells is desired it is a further object of my invention to mount additional blocks similar to those between the cell forming plates above and below the cells.

It is a further object of my invention to provide an improved guard for the free ends of the binders, the guard serving to tie the several units or cells together and being held in position by the same means which holds together the several units.

With these and other objects in view which will appear as the description proceeds, my invention resides in the combination and arrangement of parts hereinafter described and set forth hereinafter.

In the accompanying drawings, wherein a convenient embodiment of my invention is set forth, Fig. 1 is a top plan view of a set of shuttle

boxes made according to my present invention showing the same assembled and in association with the lay guides,

Fig. 2 is a front elevation of the boxes set forth in Fig. 1.

Figs. 3 and 4 are end elevations taken in the directions of arrows 3, and 4, respectively, Fig. 2,

Fig. 5 shows the several parts of one cell in perspective and detached,

Fig. 6 is a detailed rear view taken in the direction of arrow 6, Fig. 1, showing the inner end of the boxes, modified to afford additional wearing surface,

Fig. 7 is a plan view of the Bakelite floor for the cells,

Fig. 8 is a transverse vertical section through one end of a cell showing the box floor and the manner of holding it in place, and

Fig. 9 is a perspective view of a modified spacing block to form a wide mouth for the box.

Referring to the drawings, the lay 10 is shown as provided with inner and outer guides 11 and 12, respectively, which are grooved in the usual manner as at 13 for the purpose of guiding the boxes as they are shifted to different vertical positions by means of a box lifter rod 14.

As already stated the gang G of shuttle boxes is made up of a plurality of cells each complete in itself and each similar to the other cells. I have shown my invention applied to a two cell gang having upper and lower boxes B and B', but it is to be understood that the invention can be extended to provide a box having any desired number of cells. Since the boxes B and B' are alike a description of one of them, namely the upper box, will suffice for both.

In forming the box I provide a top member or plate 20 made of flat sheet metal, such as steel, and provide the inner end thereof with an enlarged head 21 having front and back bolt holes 22 and 23, respectively. A small tongue 24, shown in Fig. 5, projects inwardly from the rear part of the head 21 to extend into the groove 13 of the guide 11. The intermediate part 25 of the plate 20 is of reduced width while the outer or left end 26 as viewed in Fig. 5 is enlarged as at 27 and provided with bolt holes 28. A binder pin hole 29 is also provided which is preferably forward of the holes 27, and as is the case at the opposite end of the plate the outer or left end is provided with a tongue 29 to enter the groove 13 of the outer or left guide 12.

The head 21 extends rearwardly as at 30 beyond the rear edge 31 of the plate which extends from the extension 30 to the opposite end of the plate.

As shown in Fig. 3 for instance the rear edge of the plate is bent downwardly to form an upper back wall 32 for the top rear edge of the shuttle. This wall 32 may be struck from an original plate 5 having a width represented by the full transverse dimension of the head 21, this construction permitting the extension 30 and the wall 32 to be formed without wasting material. The bolt holes 23 are in the extension 30 so as to lie behind the 10 front surface 33 of the wall 32, see Fig. 3.

The lower plate 35 as shown in Fig. 5 is similar to the upper plate but of the opposite hand and has an upstanding bottom rear wall 36 similar to and in alignment with wall 33 and has also a 15 rear extension 37 with rear bolt holes 38 similar to the parts 23 and 30 of the upper plate. The lower plate also has a tongue 39 similar to the tongue 24. The extension 37 is a part of a head 40 similar to head 21 and has front bolt holes 41 20 similar to holes 22. At the other end of the lower plate 35 there is a second head 45 having bolt holes 46 and a tongue 47 and also a binder pin hole 48 corresponding to the hole 28.

The tops and bottoms of the cells may be made 25 of appropriate material such as sheet steel and are the same with the exception that they are of opposite hands, the shuttle engaging walls 32 and 36 extending toward each other.

For each cell I provide three blocks 50, 51 and 30 52, respectively, which as shown in Fig. 5 are formed preferably of a composition material, such as Bakelite. The block 51 has bolt holes 55 to register with the holes 27 and 46 and also has a tongue 56 to be located between the top and bottom 35 tongues 29 and 47. The inner end of the block 50 may be rounded as at 57 to avoid possible injury to the shuttle and the block is also provided with a tapped hole 58 to receive a screw 59 which holds binder spring 60 in place. The tops 40 and bottoms of the block 50 are flat and parallel and the height of this block, as well as the height of the other blocks, determines the vertical dimension of the cell which in turn is regulated by the height of the shuttle. The plates 29 and 35 45 are so constructed, and the rear walls 32 and 36 are of such height as to permit the use of a variety of heights of blocks so that the top and bottom plates may be used to accommodate shuttles of differing heights.

Block 51 has a pair of bolt holes 61 which register with upper and lower holes 22 and 41, respectively, and the inner rear edge of this block may be rounded as at 62 to facilitate entry of the shuttle into the box. The rear surface 63 of 55 block 51 may be parallel to the back of the box and assist in defining the mouth of the cell.

In certain looms it is desirable to have a shuttle box with a so-called wide mouth to facilitate 60 thread control, while in other looms the ordinary mouth which is only slightly wider than the shuttle is satisfactory. In order to meet both of these conditions I provide two types of blocks 51, that shown in Fig. 1 being for the narrow mouth, and that set forth in Fig. 9 being used to form a 65 wide mouth. When a wide mouth is desired the block is narrower, as indicated in Fig. 9 at 65, and a rear surface 66 lies farther forward with respect to the box back than does surface 63 of block 51. By the provision of these two types of 70 blocks I am able to construct a shuttle box which may have either the wide or the usual mouth.

The third block 52 may have a flat front face 70 and is provided with two bolt holes 72 which register with top and bottom bolt holes 23 and 38 and this block also has a guide tongue 73 ly-

ing between the tongues 24 and 39. The front surface 70 is preferably in alignment with the inner surfaces of the walls 32 and 36, as suggested in Fig. 3 so as to provide a smooth surface for the back of the shuttle as the latter enters the box. 5

When assembling the two units shown in Fig. 2 the blocks are inserted between the plates as suggested in Fig. 5 and then the plates aligned, after which bolts 80 for the outer end of the gang are passed through the holes 27, 55 and 46 of each 10 cell and clamped tightly by nuts 81. In a similar manner bolts 83 are passed through the aligned holes 23, 72 and 38 of each cell and held in place by nuts 84. The clamping of top and bottom plates of these cells against the blocks holds the 15 latter rigidly in place and enables them to space the plates 29 and 35 the proper amount for the shuttle to be used. The bolts also hold the tongues 24 and 39 at the inner end of the box tightly against the top and bottom respectively 20 of the tongue 73 to prevent undue wear of the latter as the boxes rise and fall. This same condition exists also at the other end of the box with respect to tongue 56.

In order that the box structure may be complete I have set forth binders 90 which, however, form no part of my invention nor is my present invention concerned with the method of mounting them, which includes a binder pin 91 to pass through the aligned holes 28 and 48 and also 30 through cylinders 92 which may afford an eccentric mounting for a casting 93 secured to the binder 90. As shown herein each binder has an inwardly projecting tongue 95 to limit outward motion of the binder when struck by the incom- 35

A guard 100 for these tongues 95, however, is a part of my present invention and includes a single piece of metal which is common to all the cells, having horizontal top 101 and bottom 102 wings 40 respectively which are clamped against the top plate 29 of the upper cell and lower plate 35 of the bottom cell, respectively, by bolts 103 which pass through holes 28, 60 and 46. In this way the last named bolts hold the guard, the forward 45 end of the heads 21 and 40, and the blocks 51 tightly in place. The guard may include a vertical web 106 and arms 107 and 108 struck parallel to the floors of the boxes. The upper arm 107 and the top wing 101 confine the tongue 95 of 50 the upper box, while the lower tongue lies between the arms 107 and 108.

A bracket 110 may be secured in any approved manner as by rivets 111 to the bottom cell to provide connection with the box lifter rod 14, and it 55 is to be understood that the latter derives its reciprocating movement from any approved form of box motion.

The structure and method of assembly already set forth provides a gang of boxes the floors of 60 which are metallic, but it may be desired to use a non-metallic floor, in which case I provide a floor plate 120 made of composition material, such as Bakelite, having inner and outer tongues 121 and 122 to align with tongues 39 and 47, respectively. This plate may have rear inner bolt holes 123 for the bolts 83, forward inner bolt holes 124 for the bolts 103, and outer bolt holes 125 for the bolts 80. Each of the plates 120 may also be provided with a perforation 126 for the binder 70 pin 91. When used the plate 120 will be located below the blocks 50, 51 and 52 of the associated cell and will be held in place by these blocks and the pressure of the tie bolts. Plates 120 lie flat along the bottom plate 35 of each cell and serve 75

to provide an improved floor for the shuttle entering the cell.

Should it be desired to provide the gang of boxes with additional guide tongue areas, a block 5 130 similar to block 52 may be placed above the top plate 20 of the gang and held in place by bolts 131 which press on a wear plate 132, and in similar manner a second lower block 133 also like block 52 may be held by the bolts 131 pressing on 10 a wear plate 134, as shown in Fig. 6.

From the foregoing it will be seen that I have provided a gang of shuttle boxes built up of individual cells each complete in itself, the tops and bottoms of each cell being formed of two plates 15 which are similar to each other but of opposite hand. It will also be seen that the extension 30 provides material for the bolt holes 23 without requiring a waste of material, since the top rear wall 32 is struck down from a sheet the original 20 width of which corresponds to the width of the head 21. It will also be seen that the metallic tongues, such for instance as 24 and 39 reinforce the tongue 73 of the blocks 52. The height of the blocks is determined by and may be varied in 25 accordance with the height of the shuttle to enter the box. It will further be seen that the forward inner block may be of the form shown either at 54 or 65 depending upon the width of the box mouth. The box floor 120 formed of a smooth 30 wear resisting non-metallic material such as bakelite, is held in place by the blocks and the bolts passing therethrough.

Having thus described my invention it will be seen that changes and modifications may be made 35 therein by those skilled in the art without departing from the spirit and scope of the invention and I do not wish to be limited to the details herein disclosed, but what I claim is:

1. In a shuttle box for looms, a top plate of 40 sheet metal to form the upper part of the box, a guide tongue projecting from the top plate, a bottom plate of sheet metal similar to the top plate, a guide tongue projecting therefrom, a floor plate resting on the bottom plate and formed 45 of wear resisting composition material, a tongue formed on the floor plate, a spacing block located between the floor plate and the top plate, a guide tongue on the block, and means passing through the plates and block to hold the tongues in alignment and the plates adjacent the block against the latter.

2. In a shuttle box for looms, a top plate of 55 sheet metal, an integral wall depending from the top plate, a rearward extension from the top plate projecting behind the rear wall, a bottom plate, an upwardly extending wall in vertical alignment with the wall of the top plate integral with the bottom plate, an extension on the bottom plate projecting behind the front of the walls, a spacing block located between the extensions and having a shuttle engaging surface in alignment with the front surfaces of said walls, a guide tongue on the block located behind said front surfaces, and means to bolt the plates to the 60 block.

3. In a loom having a shuttle box guide provided with a guide groove, a box top forming element having a tongue, a box floor element having a tongue in vertical alignment with the tongue 70 of the top element, a block located between the plates and having a tongue in alignment with the tongues of the elements, a block similar to the block between the elements mounted on top of the upper element and having a tongue, and means

passing through the blocks and elements to hold the tongues of the blocks and elements in alignment for sliding cooperation with the groove, said means holding the ends of the tongues on the blocks adjacent the elements in close contact 5 with the tongues on the elements.

4. In a loom having a shuttle box guide provided with a guide groove, a top box plate of sheet metal, a bottom box plate of sheet metal, a floor plate on the bottom plate and having a tongue to 10 enter the guide groove, a spacing block between the top plate and floor plate, a guide tongue on the block to enter the guide groove, and means to hold the plates and block together with the tongues of the floor plate and block in alignment. 15

5. In a shuttle box for looms, a top sheet metal section disposed horizontally and having perforations therein, a bottom sheet metal section disposed horizontally and spaced from the top section and having perforations therein in vertical alignment with the perforations of the top section, a non-metallic wear resisting floor lying on the bottom section and having perforations vertically aligned with the perforations of said sections, spacing means between the top section and said non-metallic floor and having vertical perforations in vertical alignment with the aforesaid perforations of said section and floor, and securing means passing through the section, spacing means and floor to hold said parts together, said spacing means being disposed entirely around the perforations in said non-metallic floor, whereby the upper exposed surface of the non-metallic floor is smooth and uninterrupted throughout all 35 20 25 30 35 of its shuttle and thread engaging area.

6. In a shuttle box for looms, a top horizontally disposed sheet metal section having perforations extending vertically therethrough, a floor below the top section extending horizontally and in the 40 form of a sheet of non-metallic wear resisting material and having perforations therein vertically aligned with the perforations of the top section, spacing blocks located between the top section and the floor and having vertical bores 45 aligning with the perforations of said top section and floor, said blocks being in contact with the upper surface of the floor and contacting said surface around the perforations of said floor, and securing means extending through the perforations of the top section and floor and the bores of the block to hold said parts together, whereby the upper surface of the floor out of of vertical alignment with the blocks is smooth and uninterrupted. 50 55

7. In a shuttle box for looms, a top horizontally disposed sheet metal section having perforations extending vertically therethrough, a floor below the top section extending horizontally and in the form of a sheet of a phenol condensation product 60 and having perforations therein vertically aligned with the perforations of the top section, spacing blocks located between the top section and the floor and having vertical bores aligning with the perforations of said top section and floor, said blocks being in contact with the upper surface of the floor and contacting said surface around the perforations of said floor, and securing means extending through the perforations of the top section and floor and the bores of the block to hold said parts together, whereby the upper surface of the floor out of vertical alignment with the blocks is smooth and uninterrupted. 65 70
